ORTHOPEDIC BOOT OR SHOE

Joseph May, Frankfort-on-the-Main, Germany

Application November 4, 1932, Serial No. 641,237
In Germany November 11, 1931

4 Claims. (Cl. 36—3.5)

Excessive bodily weight or muscular weakness, continual standing at an occupation, among other things, lead to deformation and misplacement of the feet if the foot-gear is not adapted as regards 5 its form and construction to give sufficient support against flattening or misplacement or position of pronation of the feet.

The shape and construction of the shoe must be considered to be two important complementary factors which have the duty in common of 10 caring for the correct positioning and support of the foot. The construction and stability of the shoe must afford sufficient resistance when the foot, owing to deformation and misplacement, 15 treads or forces the shoe into a shape which is physiologically incorrect.

Hand made and machine made boots and shoes which possess arrangements for this purpose have been known for years. These arrangements consist 20 of a forwardly prolonged heel cap and an insole which is in part fulled (bent up) on the outside. These arrangements, which stiffen the shoe in the region of the tarsus and make it difficult for the foot to spread, have not given good results, 25 because they gradually become forced and deformed more and more into the same incorrect position by the continual pressure of the deformed and misplaced foot. The deformation occurs still more quickly when the leather of the cap and 30 insole becomes soft and pliable owing to heat and moisture from the feet, and to moisture penetrating from the outside.

In contradistinction to the known devices, the invention provides a wide, stretched and unyielding 35 tarsal supporting band which braces the rear cap and the insole, and which from the head of the 1st metatarsal bone passes round the back of the heel and is continued on the other side of the foot to about as far as the head of the 5th 40 metatarsal bone. This stretched and unyielding band is worked into the shoe or boot between the heel cap and the upper leather in such a manner that the middle of its width coincides with that of the heel. From the heel it is directed on the 45 outer side downwards to the head of the 1st metatarsal bone and on the inner side downwards to about as far as the head of the 5th metatarsal bone. It is tightly stretched or extended in its longitudinal direction by means of tacks, and at 50 its places of attachment, which extend as far as the arched middle portion of the shoe, it is securely connected at or below the insole, with this and the upper. The supporting band can also be secured by means of the seam in the heel cap 55 between the cap and the upper leather or at the

sides of the heel cap. This tarsal supporting band can be of any desired width at the places where it is connected or attached to the sole according as the foot is to be supported by the shoe to a greater or less extent. It encloses the tarsus and the metatarsus in the longitudinal or walking direction from the sides and the sole without hindering the development of the foot. In particular, it supports the part of the foot which takes the weight, so that this cannot spread out either 10 centrally or laterally, and it prevents rotation of the heel bone and, therefore, bent positions of the foot.

With a foot of normal development it serves an equally useful purpose. From the first to the last 15 phase of foot development, the tarsus and metatarsus are supported in their natural position and a dislocation of the bones and muscles if the laces are loose is prevented.

In addition to the tarsal supporting band a further metatarsal supporting band of the same or a similar unyielding material may be arranged in the shoe. This band beginning behind the head of the metatarsus, that is to say leaving this free, supports or encloses the metatarsus in a transverse direction. This metatarsal supporting band can be worked into the shoe between the upper leather and the lining or also below the lining. It runs in such a way as to act as a means for preventing the spreading of the foot when the 20 shoe is done up, no matter whether it is done up by means of laces, buttons, snap fasteners or buckles. It thus prevents the usual spreading of the upper in the arch near the rear of the ball of the foot and treading over of the upper on the 25 lateral sides of the shoe, in case of an abducted position of the foot.

The tarsal and metatarsal supporting bands can also be connected together and worked into the upper and stretched by being tacked or sewn in the longitudinal direction of the metatarsal supporting band. The supporting bands can be so arranged that they can be tacked or sewn together with the upper or each separately, according to the extensibility of the upper leather. 40

The continuous pressure of the misplaced and deformed foot which leads to treading over and spreading of the upper leather, in particular to uneven treading of the heel cap, is taken by the highly stretched, extended and unyielding bands, 45 which no longer allow the tarsus, the heel bone and the 1st and 5th metatarsal bones to spread to any considerable extent beyond their proper limits, and they thereby prevent spreading and treading over of the upper leather at the places 50 55

where this is liable to occur owing to the excessive weight.

Owing to the tension in every phase of movement of the foot, a pull is exerted in the longitudinal direction, namely from the place of attachment of the tarsal supporting band towards the rear cap and vice versa, and the normal development of the foot is thereby facilitated.

As is known, the sole curvature of the worn shoe alters under the action of a flat foot. The heel wears away at the back, the arch flattens and the front tread of the sole is displaced further towards the back and into the arch. The shoe thus comes into the flat foot position. The foot, therefore, since it finds no support in the shoe, becomes flatter in the arch, and, consequently, longer.

Since the shoe is diagonally stretched on the inside, on the outside and from below by the tarsal supporting band, it can give way in the longitudinal direction neither towards the inside nor towards the outside and it compels the foot to tread straightly and to form a straight and natural support when walking. It thus prevents twisting and misplacement of the foot, weak ankles, weak arches and distortion of the foot.

The metatarsal supporting band supports the metatarsus in the transverse direction. It does not allow the shoe to spread out beyond the intended width, as it supports the muscles of the 1st and 5th metatarsal bones if they become too weak.

Since the metatarsal supporting band begins behind the heads of the 1st and 5th metatarsal bones, the heads of these or the so-called ball of the big toe and the little toe remain free from pressure. Owing to the 5th metatarsal bone being supported together with the remaining metatarsal bones, in addition to eliminating the cause which leads to known metatarsal troubles, the front part of the foot is held in its natural shape, and in those cases in which it already has spread it is brought back more closely to its natural shape.

Two constructional embodiments of the invention are illustrated by way of example in the accompanying drawing, in which:—

Figure 1 shows a shoe having a tarsal supporting band worked into it (in order to make this visible the upper leather is partly cut away).

Figure 2 is a cross section on the line A—B of Figure 1, and

Figure 3 shows a shoe with a tarsal and a metatarsal supporting band worked into it (in order to make the direction of these bands visible the upper leather is again partly cut away).

Referring to the drawing, *a* is the tarsal supporting band and *b* the metatarsal supporting band, both of which consist of stretched unyielding material. They can be separate from one another and lie one above the other, or they may be connected together as is shown in Figure 2.

It is important that these bands take the course described and are attached to the parts of the insole which have been described in detail in order to effect a tensioning of the shoe which does not yield and prevents deformation.

I claim:—

1. A boot or shoe having a tarsal, non-adjustable supporting band of stretched unyielding material fixedly attached at both ends to the insole and of which the middle attachment place lies behind the ball or head of the first metatarsal bone and which runs from there obliquely upwards, along the first metatarsal bone, the first sphenoid bone, the scaphoid bone, the astragalus, and the os calcis and partly surrounds and supports these, and is continued round the os calcis and from there, sloping down laterally at the os calcis and cuboid bone, along the ball of the fifth metatarsal bone, again partly surrounding and supporting this, and finally ends at the other place of attachment to the inside behind the ball or head of the fifth metatarsal bone.

2. Boot or shoe in accordance with claim 1, in which the attachment portions of the tarsal supporting band are carried at the central and lateral places of attachment further below the insole, to about the middle portion of the insole.

3. Boot or shoe in accordance with claim 1 including a second band of unyielding material, which band, while it leaves the ball or head of the metatarsal bone free, runs transversely across the shoe and is fastened at its ends to the central and lateral part of the insole or below the inside at this place and supports the metatarsal bone and prevents spreading thereof.

4. Boot or shoe in accordance with claim 1, including a second band of unyielding material, which band while it leaves the ball or head of the metatarsal bone free, runs transversely across the shoe and is fastened at its ends to the central and lateral part of the insole or below the inside at this place and supports the metatarsal bone and prevents spreading thereof, the tarsal supporting band and the metatarsal supporting band being connected together at the places where they cross, so that the free ends of the latter are directly connected at this place over their full width to the former.

JOSEPH MAY.
